US0D1041304S

(12) **United States Design Patent** (10) **Patent No.:** **US D1,041,304 S**
(45) **Date of Patent:** ** *Sep. 10, 2024

(54) **PACKAGING FOR PLANT MATERIAL**

(71) Applicant: **Podworks Corp.**, Arlington, WA (US)

(72) Inventor: **Thomas Werth**, Arlington, WA (US)

(73) Assignee: **Podworks Corp.**, Arlington, WA (US)

(*) Notice: This patent is subject to a terminal disclaimer.

(**) Term: **15 Years**

(21) Appl. No.: **29/726,750**

(22) Filed: **Mar. 5, 2020**

(51) LOC (14) Cl. **09-01**

(52) U.S. Cl.

USPC **D9/418**; D9/600

(57) **CLAIM**

The ornamental design for a packaging for plant material, as shown and described.

DESCRIPTION

FIG. 1 is a top front isometric view of a packaging for plant material, showing the new design.

FIG. 2 is a front elevation view thereof.

FIG. 3 is a rear elevation view thereof.

FIG. 4 is a left elevation view thereof.

FIG. 5 is a right elevation view thereof.

FIG. 6 is a top view thereof; and,

FIG. 7 is a bottom plan view thereof.

The broken lines are shown for the purpose of illustrating exemplary plant materials which form no part of the claimed design.

1 Claim, 4 Drawing Sheets
